TONGS

Carl S. Hedquist, Minneapolis, Minn.

Application March 2, 1942, Serial No. 432,926

3 Claims. (Cl. 294—8.5)

This invention relates to improvements in tongs.

The primary object of the invention is to provide light and conveniently usable tongs, or a pair of tongs, particularly useful in laundering operations for grasping and removing the clothes from hot water without danger of burning the hands. The tongs are not, however, limited to such work, being useful wherever an object or article need be grasped and manipulated without coming into contact with the hands.

Another object is to provide tongs of the nature in an exceedingly simple, durable and inexpensive form.

These and other more detailed and specific objects will be disclosed in the course of the following specification, reference being had to the accompanying drawing, in which—

Fig. 1 is a side elevational view of my tongs showing the legs or arms thereof as in closed or working positions in full lines and in open positions in dot-dash lines.

Fig. 2 is an enlarged elevational view of the handle end of the tongs with a cover element thereof removed to show interior construction, the legs or arms being illustrated as in their opened positions.

Fig. 3 is a cross section along the line 3—3 in Fig. 2.

Fig. 4 is a view similar to Fig. 2 but showing portions of the cover element and showing the legs or arms as in their closed or work engaging positions.

In carrying out my invention as shown in the drawing I provide a pair of leg or arm members designated generally at 5 and 6 and a handle or cap member 7, said leg or arm members being hereinafter referred to as legs. The handle member 7 is formed and constituted by a narrow, flat cap-like housing which receives and connects the legs as will presently appear and which in use may serve as a handle for manipulating the tongs.

The legs 5 and 6 are of elongated form made preferably, although not necessarily, of wood and of rectangular or rectilinear cross section as best seen in Fig. 3. At their free or work engaging ends 8 the legs 5 and 6 normally stand apart as shown, by means to be described, and at their opposite or handle ends 10 they fit together side by side into the open end 11 of the housing forming the handle member 7.

Said handle member includes a housing 13 having spaced, substantially parallel sides or side flanges 14 and an end flange 15 opposite the open end 11, the said end flange 15 being here

shown as rounded in the interests of neatness. The open face of the housing is closed, when finished, by a cover or cover plate 16 shaped to fit and with narrow flanged edges 17 adapted to telescopically engage the flanges 14 and 15. Fastening members in the form of shouldered rivets or pins 18 having diametrically reduced end stubs 19 serve to fasten the cover in place, one of such pins being located adjacent each of the open and closed ends of the housing along the longitudinal center line of the housing and with the stubs 19 extending through suitable openings in the housing and cover and riveted down as designated at 20. The depth or thickness of the housing is such as to just nicely receive the handle ends 10 of the legs while the width or space between the sides 14 is slightly greater than the combined width of the two legs as arranged side by side in said housing.

The adjacent inner sides or side faces of the handle ends 10 of the legs 5 and 6 are provided with notches or grooves 21 so positioned as to engage opposite peripheral side portions of the pin 18 next to the open end 11 of the housing, the grooves serving as clearly shown to prevent the legs from pulling lengthwise out of the housing and acting as fulcrums permitting relative oscillating or rocking movements of the legs about the axis of the pin. A bow spring, or curved spring leaf, 22 is placed near the closed end of the housing and has its spaced, normally convergent ends 23 spread apart and braced against outer sides or side surfaces of the legs. These spring ends 23 are braced between the sides 14 and the legs adjacent the extremities of the handle ends 10 thereof and the spring pressure is thus such as to urge these ends together (Fig. 2), rocking the legs about the pin 18 with which the grooves 21 engage and spreading the work engaging ends 8 apart as clearly shown.

The depth of the grooves 21 is such (less than half the diameter of the pin 18) that the adjacent inner sides of the legs are spaced apart some distance as designated at 24 thus affording clearance for rocking movements about the pin. The outer sides of the handle ends 10 of the legs are beveled off or tapered as designated at 25 also to give clearance for movements and to provide space for the spring ends 23.

In use the tongs may be held with the handle member 7 in the palm of the hand and with the thumb and fingers extended to grasp the legs 5 and 6 adjacent said handle, or the tongs may be grasped below the handle member upon the converging ends of the legs. In either event

the legs may be squeezed together by the hand bringing their ends 8 into working and grasping engagement with an article or object therebetween and by maintaining the grip said article may be manipulated at will without contact with the hand. When the squeezing pressure of the hand upon the legs 5 and 6 is released the spring 22 will immediately spread the ends 8 apart ready for the next operation. The ease and convenience of such operation and the utility of the tongs for handling such articles as clothing and removing them from hot water, will be apparent.

As the legs 5 and 6 are closed upon the work their handle ends 10 are of course spread apart flexing the ends 23 of the spring 22 as seen in Fig. 4 and the tapered or pointed shape of the legs within the housing 13 provides sufficient space for such operation.

The fastening member or pin 18 nearest the open end of the housing serves three functions. Not only does it act as a rivet for holding the cover 16 in place, but it also serves as a pivot for the legs 5 and 6 and in addition, through cooperation with the notches or grooves 21, prevents endwise displacement of the legs relative to each other and to the handle member.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. Tongs of the character described, comprising a pair of legs arranged side by side and normally converging toward one end, a handle member enclosing the extremities of the converging ends of the legs, the said handle member including a housing having more than one part and having an open end to receive the legs, a pin arranged in the housing to secure the parts thereof together and disposed adjacent the open end of the housing between the legs, the said legs

having grooves in their adjacent surfaces adapted to engage opposite sides of the pin, and said grooves cooperating with the pin to form fulcrums about which the legs may rock to draw their diverging ends together and also to prevent endwise displacement of the legs from the housing.

2. Tongs of the character described, comprising a pair of legs arranged side by side and converging toward one end, a housing member having an open end to receive the converging ends of the legs, a pin arranged in the housing near its open end and between the legs, the adjacent inner sides of the legs having grooves adapted to engage opposite peripheral side portions of the pin whereby said legs may oscillate thereabout to bring their diverging ends together, and said grooves being of such size as to engage substantially less than one half of the opposite peripheral side portions of the pins to thereby space the inner sides of the legs apart at the pin and provide clearance for such oscillating movements.

3. A pair of tongs comprising two legs arranged to normally converge toward one end and diverge toward their other ends, a housing member having an open end to receive the converging ends of the legs and having sides to engage the legs, where they enter said open end, pivot means in the housing engaging the legs and permitting relative oscillating movements thereof to spread their converging ends and draw their diverging ends together, spring means braced between adjacent sides of the housing member and outer side surfaces of the legs to yieldably resist spreading movements of the converging ends of the legs, and the said outer side surfaces of the legs within the housing member being tapered toward their extremities to provide spaces for said spring means between these surfaces and the adjacent sides of the housing member.

CARL S. HEDQUIST.
